UNITED STATES PATENT OFFICE.

WILLIAM WERNER, OF MEXIA, TEXAS.

STANDING-VALVE-RELEASING MEANS.

Application filed November 16, 1925. Serial No. 69,308.

To all whom it may concern:

Be it known that I, WILLIAM WERNER, a citizen of the United States, residing at Mexia, Texas, have invented a certain new and useful Improvement in Standing-Valve-Releasing Means, of which the following is a specification.

My invention relates to means for raising the standing valve, in a deep well reciprocating pump, from its seat so that the fluid above the valve may be drawn out of the tubing from above the said valve when the tubing is being raised from the well.

It is a common difficulty, when the tubing of a deep well is removed, especially in oil wells, that the standing valve at the lower end of the tubing remains closed and cannot be raised, the tubing therefore remains full of oil after the plunger has been withdrawn, and each section of the tubing, when unscrewed from the adjacent lower section, spills its contents over the floor of the derrick, not only wasting the oil, but causing inconvenience and discomfort to the operators.

It is an object of my invention to provide means whereby the standing valve may be raised from its seat before the tubing is withdrawn from the well, thereby allowing the oil to drain out of the tubing, and avoiding the usual waste of oil ordinarily experienced.

It is desired that the valve be raised with a minimum amount of manipulation and in a positive manner which will not fail to work under all circumstances.

Referring to the drawing herewith, Fig. 1 is a central longitudinal section through the lower end of a pump barrel showing my invention installed therein. Fig. 2 is a transverse section on the plane 2—2 of Fig. 1. Fig. 3 is a similar section on the plane 3—3 of Fig. 1. Figs. 4 and 5 are similar transverse sections on the planes 4—4 and 5—5 of Fig. 1, respectively. Like numerals of reference are applied to like parts in all the views.

In Fig. 1 the pump barrel 1 is shown as positioned within the upper end of the liner 2, projecting into the casing 3 in the usual manner. The casing 3 has a shoe at its lower end, and the liner 2 has a shoe 5. The lower end of the liner is perforated at 6 to allow the entrance of fluid from the well

therethrough. The liner has at its extreme 55 lower end a tube 7 connected to the perforated portion by a collar 8. A cap 9 closes the lower end of the tube 7, preventing the entrance of fluid from that portion of the well.

The pump barrel 1 is of the usual construction, having a plunger adapted to reciprocate therein, said plunger being shown generally at 10. It has the usual ball valve 11 at its lower end, fitting within the valve 65 cage 11.

The standing valve in this construction is housed within a nipple 12 of slightly larger diameter than the working barrel 1, and is connected to the lower end of the working 70 barrel by a collar 13. The valve seat 14 comprises a somewhat disc shaped block threaded for engagement within the lower end of the valve housing 12, and has a central downwardly tapered seat 15 therein to receive a valve 16 which is tapered downwardly to fit within the valve seat 15, the lower end being somewhat truncated, and being positioned to fit within the upper end of a tube 17 which will be later described. 75 The upward movement of the valve 16 is limited by a valve cage 18 which is screwed to the valve seat, as shown at 19, in the usual manner.

A sleeve 20 is threaded to engage the lower end of the valve housing, said sleeve having a swivel connection at its lower end with a coupling member 21. To accomplish this swivel connection, the lower end of the sleeve 20 is formed with a short inwardly 80 turned flange 22, said flange being adapted to engage below a flange 23 on the upper end of the collar 21. Said collar 21 is threaded externally for attachment on its outer side to a perforated pipe 25 which serves as a 85 mud anchor. Said mud anchor extends downwardly for some distance below the connecting collar, and is perforated to allow the passage of fluid therethrough. Its lower end is closed by means of a plug 25. 90 The mud anchor is adapted to be held non-rotatably within liner 2, and to accomplish this purpose a series of springs 27 are secured on the outer face of the mud anchor, and adapted to bear against the inner face 95 of the liner. Said springs 27 are straps of resilient metal bowed outwardly midway of their ends to press against the liner. The

upper and lower ends are secured to a pin or rivet 29 which extends through the end of the spring and through a slot 30 in the mud anchor. The spring is thus adapted to be compressed to fit within liners of different sizes, and to press tightly against the liner to resist rotation of the inner pipe or mud anchor. If desired, the strap of metal which forms the spring 27 may be undercut, and provided with a sharp outer edge 31, as shown in Fig. 4. This sharpened edge is adapted to cut into the outer pipe when it is attempted to rotate the mud anchor in a right hand direction, and more efficiently resist the attempt to rotate the same.

On the inner side of the collar 21 is threaded a pipe 32 which is imperforate, and acts as a gas anchor to prevent the accumulation of gas within the chamber of the standing valve. This pipe extends a considerable distance below the valve, its length being determined by the particular installation in which it is used.

The collar 21 has a spider adapted to support the tube 17 previously referred to. This spider comprises a central ring 33 connected with the collar by means of radial arms 34 as shown in Fig. 3. The ring 33 is threaded on its inner side to engage the threaded lower end 35 of the tube 17. The threaded engagement is a so-called left hand engagement, and the tube is therefore adapted to be disconnected from the ring by rotation in a righthand or clockwise direction as viewed from above. A longitudinal slot 36 is cut through the tube 17, and a diametrical pin or bar 37 extends through said slot, and is secured at its opposite ends within the housing 20 (see Fig. 2). The bar is upset or riveted at each end so as to be fixed in position within the valve housing.

In operating this device, it is obvious that in the ordinary operation of the pump the swivel connection above described will have no particular function. When it is desired to withdraw the pump from the well, however, the sucker rod and plunger will be first withdrawn from the pump barrel. In doing so, the pump barrel will be filled with oil following the plunger upwardly to the surface. This oil will be discharged from the barrel so as to empty the same by rotating the pump barrel in a right-hand direction. This will cause the rotation of the sleeve 20 relative to the collar 21 and the remainder of the apparatus below. By rotating the sleeve 20, the cross bar or pin 37 will act to rotate the tube 17 also, and as the rotation of the sleeve 20 is in a right-hand direction, the tube will be unscrewed from the ring 33 in which it fits. The said ring 33 and the gas anchor and mud anchor below the same will be held non-rotatable

through the action of the springs 27. Unscrewing the tube 17 will cause it to move upwardly against the lower end of the valve 16, thus acting to raise the valve from its seat into the position shown in Fig. 1. This will release the oil above the valve, allowing it to drain away, so that the pump barrel and tubing may be withdrawn upwardly from the well, together with the standing valve secured thereon.

The advantages of this construction will be obvious to one skilled in the art. The valve may be raised from its seat sufficiently to drain the oil from the pump barrel by only a few rotations of the barrel. As the usual joints in the pipes connected with the pump barrel are threaded in a right hand direction, they will not tend to unscrew by the rotation thereof in a right hand direction. The action, therefore, upon the releasing tube 17, will be a positive one, and the tube will be screwed upwardly, tending to quickly release the valve. It is simple and positive in its action, and may be adapted for use with pumping devices of different makes. While I have shown it adapted for use in a pump of the construction described, it is obvious that it is adapted for use with pumps of quite different form and construction.

Having thus described my invention, what I claim as new and desire to protect by Letters Patent is:

1. In a pump, a pump barrel, a standing valve at the lower end thereof, comprising a housing, a valve seat therein, a valve in said seat formed to taper downwardly below said seat, a collar below said valve housing, a spider within said collar having a central internally threaded ring thereon, a tube having its lower end threaded in a left hand direction to fit within said ring, means to hold said collar against rotation, and means connected with said valve housing to rotate said tube, and screw it upwardly in said ring into contact with said valve, and raise said valve from its seat.

2. In a pump, a pump barrel, a standing valve housing at the lower end thereof, a valve seat in said housing, a downwardly projecting valve in said seat, a sleeve below said valve housing, means to hold said collar stationary, a swivel connection between said valve housing and said collar, a central ring connected with said collar, a tube having a left-hand threaded engagement with said ring, and extending upwardly below said valve, and means connected with said valve housing whereby said tube may be rotated when said pump barrel is rotated, to raise said valve from its seat.

3. In a pump a standing valve housing, a valve therein, a collar below said valve, means to hold said collar from rotation, a spider on said collar, a member having a left

hand threaded engagement with said spider, and means connected with said valve housing to cause said member to rotate with said housing and move said member upwardly 5 against said valve.

4. In a pump, a pump barrel, a standing valve housing thereon, a valve seat in said housing, a valve in said seat adapted to project downwardly below said seat, a collar 10 below said housing, means connecting said housing rotatably with said collar, means to hold said collar from rotating, a member having a threaded connection with said collar below said valve, and means connected 15 for rotation with said housing to raise said member and said valve.

5. In a pump including a standing valve housing, a valve seat, and a valve in said seat, the combination of a collar below said 20 valve housing, a sleeve on said housing having a swivel connection with said collar, a central threaded ring in said collar, a tubular post connected in said ring, and means on said sleeve connected with said 25 post to cause the upward movement of said

post against said valve when said sleeve is rotated.

6. In a pump, including a pump barrel, a standing valve housing thereon, a valve seat in said housing, and a valve in said seat, 30 the combination of a collar, and an upwardly projecting post in said collar below said valve, said post being adapted to move upwardly against said valve when said housing is rotated.

7. In a pump, including a pump barrel, a standing valve housing thereon, a valve seat in said housing, and a valve in said seat, the combination of a collar having a 35 swivel connection with said housing, a post below said valve having a left hand threaded engagement with said collar, means to prevent rotation of said collar, and means whereby said post may be rotated with said 40 housing to raise said valve.

In testimony whereof I hereunto affix my signature this 11th day of November, A. D. 1925.

WILLIAM WERNER.
